US00D840024S

(12) **United States Design Patent** (10) **Patent No.:** **US D840,024 S**
(45) **Date of Patent:** **** Feb. 5, 2019**

(54) **ON-BODY INJECTOR FOR DRUG DELIVERY**

(71) Applicant: **AMGEN INC.**, Thousand Oaks, CA (US)

(72) Inventors: **Brian Stonecipher**, Newbury Park, CA (US); **Craig Lester**, Westlake Village, CA (US); **R. Paul Mounce**, Burbank, CA (US); **Eva Stump**, Newbury Park, CA (US); **Michel D. Arney**, Wellesley, MA (US); **Maxwell Franklin Bischoff**, Somerville, MA (US); **Laurie Burns**, St. Louis, MO (US); **Gregg Allen Flender**, Bedford, MA (US); **Barbara Hartigan**, Newbury Park, CA (US); **Gaurav Rohatgi**, Waltham, MA (US); **Bryce George Rutter**, Saint Louis, MO (US); **Megan Marie Rutter**, Saint Louis, MO (US); **Kristin Leigh Sjo-Gaber**, West Roxbury, MA (US)

(73) Assignee: **AMGEN INC.**, Thousand Oaks, CA (US)

(**) Term: **15 Years**

(21) Appl. No.: **29/634,319**

(22) Filed: **Jan. 19, 2018**

(57) **CLAIM**

The ornamental design for an on-body injector for drug delivery, as shown and described.

DESCRIPTION

FIG. 1 is a perspective view showing a new design for an on-body injector for drug delivery;

FIG. 2 is a top view of the on-body injector of FIG. 1;

FIG. 3 is a bottom view of the on-body injector of FIG. 1; FIG. 4 is a right-side view of the on-body injector of FIG. 1;

FIG. 5 is a left-side view of the on-body injector of FIG. 1; FIG. 6 is a back view of the on-body injector of FIG. 1; and, FIG. 7 is a front view of the on-body injector of FIG. 1. The dashed lines showing portions of the on-body injector are included for the purpose of illustrating environment and form no part of the claimed design.

1 Claim, 3 Drawing Sheets
